UNITED STATES PATENT OFFICE.

WALTER BACKUS BROWN, OF BORDENTOWN, NEW JERSEY.

NECKTIE-FASTENER.

SPECIFICATION forming part of Letters Patent No. 403,913, dated May 28, 1889.

Application filed January 30, 1889. Serial No. 298,111. (No model.)

To all whom it may concern:

Be it known that I, WALTER BACKUS BROWN, a citizen of the United States, residing at Bordentown, in the county of Burlington and 5 State of New Jersey, have invented new and useful Improvements in Necktie-Fasteners, of which the following is a specification.

The invention relates to a necktie-fastener; and it consists in a certain novel construction and combination of parts, fully set forth hereinafter in connection with the accompanying drawings, and specifically pointed out in the appended claims.

In the drawings, Figure 1 is a view of a 15 necktie, showing the improved fastener applied in the operative position. Fig. 2 is a transverse sectional view of the same. Fig. 3 is a detail view of the pliable wires comprising the fastener.

20 Referring by letter to the drawings, A designates a necktie, which may be of any preferred or ordinary shape or kind, in the band B (or in the portion which passes around the neck of the wearer) of which is formed a slit 25 or button-hole, C.

The fastener consists of two approximately parallel pliable wires, D D, which are arranged, respectively, on opposite sides of the said button-hole and parallel with the length 30 of the band. The said wires may be held in sheaths E E on the edges of the button-holes, as shown in the drawings, or may be free, as desired.

The pliable wires are provided at their ends 35 with the eyes E' E', through which the stitches are passed to secure the wires to the band of the tie. These eyes also prevent the wires from running through the tie and projecting from the same to annoy the wearer.

40 The operation of the improved fastener is obvious. When the tie is passed around the neck of the wearer, the collar-button at the back is inserted in the button-hole C between the pliable wires, and when the tie is secured in

front, and thereby drawn tight, the longitudinal tension of the band B draws the said wires close together at their centers, and thereby clamps between them the shank of the collar-button. This prevents all vertical movement of the band of the tie, so annoying to the wearer, 45 and it is fastened simultaneously with the tying of the necktie.

The fastener is readily applied to the tie and may be very cheaply manufactured owing to its simplicity. In a four-in-hand tie the 55 button-hole should be about two inches long, in order to allow of some longitudinal movement of the tie in adjusting the same; but in other forms of ties the button-hole may be shorter. The wires are preferably pliable, in 60 order to enable the tie to be folded. When the tie is fastened, the said wires stiffen the edges of the button-hole sufficiently to prevent all displacement of the tie.

Having thus described the invention, I 65 claim—

1. The necktie A, having a band, B, provided with an elongated button-hole, C, at the back, in combination with the two independent stiffening-wires D, secured at their ends 70 to said band, their bodies being curved outwardly and lying along the edges of said button-hole, whereby the tension of the band B will draw them toward each other, as and for the purpose set forth.

2. The necktie-band having a longitudinal button-hole therein, and the pliable stiffening-wires fitting in sheaths in the edges of the said button-hole and provided at their ends with eyes to receive stitching, substantially as specified.

In testimony that I claim the foregoing as my own I have hereto affixed my signature in presence of two witnesses.

WALTER BACKUS BROWN.
